UNITED STATES PATENT OFFICE.

JOHN CALVERLEY, OF OREGON CITY, OREGON.

DESIGN FOR A SAW-SET.

46,766.

Specification for Design.

Patented Dec. 15, 1914.

Application filed September 5, 1914. Serial No. 860,463. Term of patent 3½ years.

To all whom it may concern:

Be it known that I, JOHN CALVERLEY, a citizen of the United States, residing at Oregon City, in the county of Clackamas and State of Oregon, have invented a new, original, and ornamental Design for Saw-Sets, of which the following is a specification, reference being had to the accompanying drawing, forming a part thereof.

The figure is a perspective view of a saw set, showing my new design.

I claim:

The ornamental design for a saw set, as shown.

JOHN CALVERLEY.

Witnesses:

B. N. HICKS,

C. W. PARRISH.
